DESIGN FOR A SHOE OR SIMILAR ARTICLE

Adolph Wertheim, Brooklyn, N. Y.

Application January 16, 1940, Serial No. 89,502

Term of patent 3½ years

To all whom it may concern:

Be it known that I, Adolph Wertheim, a citizen of the United States, residing in Brooklyn, in the county of Kings, in the State of New York, have invented a new, original, and ornamental Design for a Shoe or Similar Article, of which the following is a specification, reference being had to the accompanying drawing, forming part thereof.

showing my new design, the opposite side presenting substantially the same appearance as the side shown.

I claim:

The ornamental design for a shoe or similar article, substantially as shown and described.

ADOLPH WERTHEIM.
